UNITED STATES PATENT OFFICE.

HENRY SWIHART, OF MASSILLON, OHIO.

STEAM-BOILER.

SPECIFICATION forming part of Letters Patent No. 369,302, dated August 30, 1887.

Application filed December 30, 1886. Serial No. 223,000. (No model.)

To all whom it may concern:

Be it known that I, HENRY SWIHART, a citizen of the United States, residing at Massillon, in the county of Stark and State of Ohio, have invented certain new and useful Improvements in Steam-Boilers; and I do hereby declare that the following is a full, clear, and exact description of the same, reference being had to the annexed drawings, making a part of this specification, and to the letters and figures of reference marked thereon, in which—

Figure 1 is a longitudinal section of the boiler, showing its different parts in proper adjustment. Fig. 2 is an end view looking toward the fire-box, showing door-plate removed. Fig. 3 is a detached view of a small portion of the boiler, showing manner of attaching the water-retaining plate to the boiler proper. Fig. 4 is a view of a portion of the valve-rod, showing the handle or knob attached thereto. Fig. 5 is a view of portion of fire-box.

The present invention has relation to steam-boilers designed and calculated to be used with portable or traction engines; and its nature consists of the different parts and combination of parts hereinafter described, and particularly pointed out in the claims.

Similar letters of reference indicate corresponding parts in all the figures of the drawings.

The object of my invention is to provide steam-boilers for traction or locomotive engines, subject to changes in their level, that can be easily taken care of and without any danger of destroying the crown-sheet by sudden changes of level.

In the accompanying drawings, A represents the boiler, which may be substantially of the form shown, or it may be of any other desired form, reference being had to its construction, so as to properly attach a water-retaining plate, as hereinafter described.

The normal water-line is indicated by the heavy dotted line XX, Fig. 1, when the boiler is placed or standing level. The fire-box B is located substantially as shown in Fig. 1, and is attached to the boiler A in any suitable and convenient manner. The fire-box B is provided with the water-chambers C and D, said chambers being located substantially as shown

in Fig. 1. The partition a is located as shown in Fig. 1, and is for the purpose hereinafter described.

The water-retaining plate E is located substantially as shown in the drawings, and as shown it is adjusted a short distance above the front or forward portion of the crown-sheet F. This water-retaining plate is attached at its edges to the boiler A, as shown in Figs. 2 and 60 3, and is inclined forward and upward, as shown in Fig. 1. The top or upper edge of this water-retaining plate E is about even or level with the normal water-line XX.

Between the water-retaining plate E and the crown-sheet F is located the valve G, said valve being operated by means of the rod H and the handle or knob I. In use this valve G is open when the boiler is moving over level ground or is standing on a level, and closed 70 when the boiler is descending a grade or set at an angle. It will be seen that by my peculiar arrangement the water contained in the boiler is free to circulate within the entire limits of the boiler and water-chambers when 75 the valve G is open. It will also be seen that when the valve G is closed the water cannot communicate with all the different parts of the boiler except as it flows over the top of the retaining-plate E, thereby holding or damming a 80 sufficient quantity of water to fully cover the crown-sheet F when descending grades.

For the purpose of preventing the water from leaking through below the top of the water-retaining plate E the felt h is placed between the flanges on the plate E and the boiler, as shown in Fig. 3.

The water is fed into the boiler A through the pipe J, said pipe being located at any desired point in the rear of the partition a, the valve G being open, as indicated by the dotted line, thereby offering no resistance to the flow of water to the boiler and water-chambers. The partition a is for the purpose of separating the water between the chambers C and D, and at the same time holding the water located around the fire-box in position when the engine is descending a grade. The valve-rod H is held in proper position by means of a screw-thread, as shown in Fig. 4.

The valve G should be located at one side of the crown-sheet, so that water will flow into

the boiler A before the crown-sheet is fully covered.

Having now fully described my invention, what I claim as new, and desire to secure by 5 Letters Patent, is—

1. The combination of the boiler-shell, the water-retaining plate E, the boiler A, the felt h, and the valve G, substantially as and for the purpose specified.
- 10 2. The combination of the boiler A, the fire-box B, water-chambers C and D, the water-retaining plate E, located substantially as

shown, the crown-sheet F, the valve G, with means for operating said valve, and the partition a, substantially as and for the purpose 15 specified.

In testimony that I claim the above I have hereunto subscribed my name in the presence of two witnesses.

HENRY SWIHART.
